Primary Examiner — Cynthia Ramirez*Assistant Examiner* — Michael A Maharajh(57) **CLAIM**

The ornamental design for a skin exfoliating device, as shown and described.

DESCRIPTION

FIG. 1 is a perspective view of a skin exfoliating device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the skin exfoliating device with a lid in a closed configuration.

The broken lines in the drawings are for the purpose of illustrating portions of the skin exfoliating device that form no part of the claimed design.

1 Claim, 8 Drawing Sheets(56)
